JOAH BROGDEN, OF MELROSE PARK, PENNSYLVANIA, ASSIGNOR TO DAVID LUPTON'S SONS COMPANY, OF PHILADELPHIA, PENNSYLVANIA, A CORPORATION OF PENNSYLVANIA

RADIATOR HANGER MEANS

Application filed November 16, 1928. Serial No. 319,788.

This invention relates to means for supporting wall radiators in suspension and more particularly to installation of radiators under the sills of windows.

In the main, this invention is directed toward affording suspension support for radiators of the specific type referred to entirely independent of the window frames so as to preclude distortion and imposition of strains on the latter. My invention is, accordingly, especially advantageous with window structures embodying frames of sheet metal where distortion or strain is likely to interfere with the free operation of the sashes, and I have accordingly hereinafter shown and described said invention in connection with such use.

Other objects and attendant advantages will be manifest from the detailed description which follows when considered with the accompanying drawings.

Fig. I is a fragmentary elevation of the inside of a window structure embodying the radiator hanger means of my invention.

Fig. II is a staggered fragmentary plan section taken as indicated by the arrows II—II in Fig. I.

Fig. III is a vertical section, taken as indicated by the arrows III—III in Fig. I.

Fig. IV is a detail section, taken as indicated by the arrows IV—IV in Fig. I.

Figs. V and VI are perspective views of certain of the parts of my improved radiator hanger means.

The window herein depicted comprises a frame 10 constructed throughout from sheet metal with hollow side jambs 11, that afford vertical grooves 12 for guidance of sliding sashes—not shown, and a hollow bottom or sill portion 13. As shown, the frame 10 is set into an opening 14 provided for it in the masonry building wall 15, and sealed in place with cementitious bonding material conventionally indicated at 16, in Figs. II and III. The frame 10 may be of any standard or approved construction, and, per se, does not form a part of this invention.

Coming now to the radiator hanger means featured herein, it will be observed that the same comprises a metallic suspension bar 20, which, in the present instance, is of T cross

section. As shown in Fig. V, the upper leg of the vertical or head flange 21 of the bar 20 is cut away as at 22, and the lower leg at 23, with formation of end tongues 24, as continuations of the medial web 25.

To support the suspension bar 20 at the ends, I provide right and left hand anchorages 26, 26a, one such being illustrated in perspective in Fig. VI. Each of these anchorages 26, 26a has a portion 27 cut from metallic channel-bar stock affording a longitudinal recess or groove 28 to receive the corresponding end tongue 24 of the bar 20; and a diagonally flanking wing-like portion 29 cut to rectangular configuration from sheet metal, the two portions being permanently secured together in the angular relation shown in Fig. VI by riveting or welding. To facilitate placement in a manner to be presently explained, each anchorage 26 or 26a is provided with gage lugs 30, 31 which may be constituted by turning down corner projections of the wing portion 29 beyond the region of juncture with the grooved portion 27, see Fig. VI. The anchorages 26, 26a are placed in the positions illustrated at opposite sides of the bottom of the window opening 14 incidental to erection of the wall 15, with the gage lugs 30, 31 respectively abutting the sides of the opening and the inner face of said wall. As determined by the gage lugs 30, 31, the portions 27 of the anchorages 26, 26a take transverse positions along the sides of the window opening 14 with their longitudinal grooves or recesses 28 in opposed relation. As building of the wall proceeds, the anchorages 26, 26a are embedded in the masonry with only the grooves or recesses 28 exposed.

Upon completion of the wall 15 and setting of the window frame 10 into the opening 14, the suspension bar 20 is brought up and its tongue ends 24 engaged in the grooves 28 of the anchorages 26, 26a.

To facilitate alignment with assurance of true parallelism of the suspension bar 20 with respect to the plaster line L (Fig. II and III) predetermined upon, I provide angular spacing pieces such as shown at 32, see Figs. I and IV. These spacing pieces 32 may be of sheet metal and welded or otherwise attached to

the horizontal web 25 of the bar 20, near the ends 24. Accordingly, as the bar 20 is pushed inwards, the vertical flanges of the spacing pieces 32 come to a stop against the inner faces of the wall 15, thereby determining the proper position of the latter with its head flange 21 spaced at a distance from the wall 15, as shown in Fig. IV. After placement as just described, the suspension bar 20 may be secured in any convenient manner, for example, by forcing wedges 33 into the recesses 28 of the anchorages 26, 26a over the ends 24 of the said bar, see Figs. I and III.

In order to conceal the suspension bar 20 I supplement the window frame 10 with a "stool" 35 of sheet metal which, as shown in Fig. III, is detachably secured by means of screws 36 to an angle piece 37 permanently fastened to the rear of the sill 13. It is to be particularly noted that while the stool 35 overhangs the top and the front of the suspension bar 20, said stool is entirely free of contact with either the latter or with the hook brackets 38 by which the radiator 39 is hung. These hook brackets 38 may be of any approved construction; but for the sake of lightness I prefer to fabricate them from stout sheet metal with an angle bend to lend the necessary rigidity. As shown in Fig. III, the tops of the hook brackets 38 are retroverted at 40 to engage over the upstanding portion of the head flange 21 of the bar 20. It is moreover to be observed, from Figs. II and III, that the suspension bar 20 is accessible through the open ends of the stool member 35 so that the hook brackets 38 can be introduced or withdrawn at any time by way of said cut-outs 22 adjacent the ends of the suspension bar.

I have thus provided a window radiator hanger means which receives its support from the masonry of the building wall so that no strains whatever are induced in the metallic window frame.

Having thus described my invention, I claim:

1. Window radiator supporting means comprising a wall of masonry, a horizontal suspension bar with associated end wedge members anchored in the masonry at opposite sides of the window opening, whereby said bar is supported and anchored independently of the window frame.

2. Window radiator supporting means comprising a wall of masonry, a horizontal suspension bar, and associated supporting members embedded in the masonry at opposite sides of the window opening, and thus supporting the bar independently of the window frame.

3. Window radiator supporting means comprising a wall of masonry, socket members embedded in the masonry at opposite sides of the window opening, and a horizontal suspension bar having its ends engaged

in said sockets so that said bar is thus supported independently of the window frame.

4. Window radiator hanger means comprising a wall of masonry, a horizontal T-section metallic suspension bar anchored independently of the window frame to said masonry along the bottom of the wall opening for said frame, in combination with a metallic stool member secured to the sill of the window frame to overreach and conceal said suspension bar. 75

5. Window radiator hanger means comprising a wall of masonry, a horizontal T-section suspension member anchored independently of the window frame to said masonry along the bottom of the wall opening for said frame, said member having terminal cut-outs in the upper leg of its head flange to enable application of the radiator hanger means, in combination with a stool member 85 detachably secured to the sill of the window frame reaching forwardly and downwardly to conceal said suspension bar.

6. Window radiator hanger means comprising a wall of masonry, a horizontal suspension bar of metal, and anchorage members also of metal to support the bar independently of the window frame, said members being embedded in the masonry at opposite sides of the wall opening for the window frame at the sill level and affording opposing transverse recesses to take the ends of the suspension bar. 95

7. Window radiator hanger means comprising a wall of masonry, a horizontal suspension bar of metal, and anchorage members also of metal to support the bar independently of the window frame, said members being embedded in the masonry at opposite sides of the wall opening for the window frame at the sill level affording opposing transverse recesses to take the ends of the suspension bar with provision for in-and-out adjustment into coincidence with a predetermined plaster line for the inner face of the wall, and means to secure the suspension bar in adjusted position. 105

8. Window radiator hanger means comprising a wall of masonry, a horizontal suspension bar of metal, and anchorage members also of metal to support the bar independently of the window frame, said members affording transverse opposing grooves along opposite sides of the bottom of the wall opening of the window to take the ends of the suspension bar and having flanking horizontal wing-like portions embedded in the masonry adjacent said window opening. 115

9. Window radiator hanger means comprising a wall of masonry, a horizontal T-section suspension bar of metal, and anchorage members also of metal to support the bar independently of the window frame, said members affording transverse opposing recesses along opposite sides of the bottom of the window opening. 125

the wall opening of the window to take the web ends of the suspension bar and having flanking horizontal-wings as well as corner lugs adapted to be embedded in masonry adjacent said window opening.

10. Window radiator hanger means comprising a wall of masonry, a horizontal suspension bar of metal; and anchorage members also of metal to support the bar independently of the window frame, said members affording transverse opposing recesses along opposite sides of the bottom of the wall opening for the window to take the ends of the suspension bar, and having a diagonally-flanking horizontal wings embedded in the masonry adjacent the window opening as well as gaging lugs to predetermine, by contact with the vertical surfaces of the masonry, proper allocation of said anchorage members incidental to placement initially.

In testimony whereof, I have hereunto signed my name at Philadelphia, Pennsylvania, this 12th day of November, 1928.

JOAH BROGDEN.
